UNITED STATES PATENT OFFICE.

WILLIAM H. HUMPHREY, OF NEW YORK, N. Y.

FLAT BRUSH.

SPECIFICATION forming part of Letters Patent No. 700,050, dated May 13, 1902.

Application filed January 25, 1902. Serial No. 91,190. (No model.)

To all whom it may concern:

Be it known that I, WILLIAM H. HUMPHREY, a citizen of the United States, and a resident of the city of New York, borough of Manhattan, in the county and State of New York, have invented new and useful Improvements 5 in Flat Brushes, of which the following is a full, clear, and exact description.

The invention relates to brushes used by 10 painters, varnishers, and other mechanics; and its object is to provide certain new and useful improvements in flat brushes, whereby the bristles are resiliently supported at the front and rear faces of the brush to insure 15 proper flexing of the bristles when the brush is in use, at the same time allowing free flow of the paint, varnish, or other material.

The invention consists of novel features 20 and parts and combinations of the same, as will be more fully described hereinafter and then pointed out in the claims.

A practical embodiment of the invention is 25 represented in the accompanying drawings, forming a part of this specification, in which similar characters of reference indicate corresponding parts in all the views.

Figure 1 is a face view of the improvement. Fig. 2 is an edge view of the same. Fig. 3 is 30 a transverse section of the same on the line 3 3 of Fig. 1. Fig. 4 is a like view of a modified form of the same, and Fig. 5 is a perspective view of the band and its extensions.

On the head A' of the handle A is secured 35 the band B, inclosing the butt-end of the bristles C, the latter being secured in place within the band by a suitable adhesive substance, such as glue, and by fastening devices, such as nails D, driven through the band B, the bristles, and the wooden core E thereof, as plainly indicated in the drawings. On the front and rear faces of the band B are 40 arranged outward extensions F, preferably made of sheet metal and soldered or otherwise fastened to the inside of the sheet-metal band B.

The extensions F are preferably lined on 45 the inside by linings G, of leather or other flexible material, and each lining preferably extends beyond the outer ends of the sides of the corresponding extension F, so that the bristles do not come in contact with the edges of the extensions F. The extensions are con-

nected with each other at or near their sides by wires or cords H, which may extend around the outside of the bristles, as plainly indicated 55 in Figs. 1 and 2, or the wires H' extend transversely through the bristles, as plainly indicated in Fig. 4.

Now by the arrangement described the extensions F and their linings G form a resilient 60 bridle for the bristles C, so that when the brush is used the bristles properly flex and immediately return to their normal position by the action of the extensions and their linings. It is understood that the side edges of 65 the bristles are open between the ends of the extensions and their linings to insure free flow of the paint, varnish, or the like.

The extension and its cushion-lining protects the bristles against being injured while 70 the brush is used.

Having thus described my invention, I claim as new and desire to secure by Letters Patent—

1. A flat brush provided with a metallic 75 band encircling the butt-end of the bristles, and having metallic outward extensions on the front and rear faces, linings of flexible material for the said extensions and extending beyond the outer ends of the extensions 80 and beyond the sides thereof, and a connection between the front and rear metallic extensions at or near the sides thereof; as set forth.

2. A flat brush provided with a metallic 85 band encircling the butt-end of the bristles and having outward extensions on the front and rear faces, linings of flexible material for the said extensions and extending beyond the same, and a connection between the front and 90 rear metallic extensions at or near their sides and comprising wires or cords extending around the outside of the bristles, as set forth.

3. A flat brush provided with a band encircling the butt-end of the bristles and secured on the head of the handle, the band having outward extensions on the front and 95 rear faces, flexible linings for the said extensions and secured thereto by eyelets, and wires or cords extending through the eyelets 100 at or near the sides of the extensions and connecting the front and rear extensions, as set forth.

4. A flat brush provided with a band en-

circling the butt-end of the bristles and secured on the head of the handle, fastening devices extending through the band and bristles and engaging the wooden core in the butt-
5 end of the bristles, the said band having outward extensions on the front and rear faces, flexible inside linings for the extensions extending beyond the outer ends of the extensions, and the sides thereof and wires or cords

connecting the front and rear extensions at 10 or near the sides thereof, as set forth.

In testimony whereof I have signed my name to this specification in the presence of two subscribing witnesses.

WILLIAM H. HUMPHREY.
